US0D1033410S

(12) **United States Design Patent** (10) **Patent No.:** **US D1,033,410 S**
(45) **Date of Patent:** **** Jul. 2, 2024**

(54) **SUPPORTING ARM FOR TELEVISION RECEIVER**

(71) Applicant: **LG ELECTRONICS INC.**, Seoul (KR)

(72) Inventors: **Yongseok Kim**, Seoul (KR); **Jiwon Park**, Seoul (KR)

(73) Assignee: **LG ELECTRONICS INC.**, Seoul (KR)

(**) Term: **15 Years**

(21) Appl. No.: **35/518,840**

(22) Filed: **Oct. 31, 2022**

(80) **Hague Agreement Data**

Int. Filing Date: **Oct. 31, 2022**

Int. Reg. No.: **DM/224813**

Int. Reg. Date: **Oct. 31, 2022**

Int. Reg. Pub. Date: **Nov. 3, 2023**

(30) **Foreign Application Priority Data**

Jun. 2, 2022 (KR) 30-2022-0022099

(51) **LOC (14) Cl.** **14-03**

(52) **U.S. Cl.**

USPC **D14/239**

(57) **CLAIM**

The ornamental design for a supporting arm for television receiver, as shown and described.

DESCRIPTION

1. Supporting arm for television receiver

1.1 : Perspective

1.2 : Rear perspective

1.3 : Front

1.4 : Back

1.5 : Left

1.6 : Right

1.7 : Top

1.8 : Bottom

1.9 : Reference

1.10 : Reference

1.11 : Reference

1.12 : Reference

1.13 : Reference

1.14 : Reference

Reproductions 1.9 and 1.10 are reference views showing the state of use that angle of a supporting arm for television receiver has been adjusted; reproduction 1.11 is a reference view showing the state of use that the claimed design is

(Continued)

installed on a television receiver; reproduction 1.12 is a reference view showing the state of use that angle of the arm has been adjusted with a television receiver; reproductions 1.13 and 1.14 are perspective views in which the portions depicted to solid lines are separated from the claimed design; the broken lines indicate portions of the article that form no part of the claimed design.
